UNITED STATES PATENT OFFICE.

MARTHA V. BAUER, OF WASHINGTON, DISTRICT OF COLUMBIA.

SANITARY PAD.

1,341,875.

Specification of Letters Patent.

Patented June 1, 1920.

Application filed October 31, 1919. Serial No. 334,784.

To all whom it may concern:

Be it known that I, MARTHA V. BAUER, a citizen of the United States, residing at Washington, in the District of Columbia, have invented certain new and useful Improvements in Sanitary Pads, of which the following is a specification.

This invention relates to pads which may be used in any case where absorbent pads are required, such as in the case of infants and invalids.

One of the primary objects of the invention is to provide a pad for the purpose stated embodying an absorbent member the purpose of which is obvious and which member may be removed or detached from the remainder of the pad and hung up to dry or it may be washed or otherwise cleansed so as to render it fit for future use.

Another object of the invention is to provide a pad of the class mentioned so constructed that the same will be highly absorbent, the absorbent member of the pad being so protected by a nonabsorbent backing member as to preclude any possibility of fluids absorbed by the first-mentioned member coming in contact with and soiling the bed clothing.

In the accompanying drawings:

Figure 1 is a perspective view of the pad embodying the present invention;

Fig. 2 is a perspective view of the pad in suspended position;

Fig. 3 is a longitudinal sectional view through the pad;

Fig. 4 is a detail sectional view similar to Fig. 3.

Corresponding and like parts are referred to in the following description and indicated in all the views of the accompanying drawings by the same reference characters.

The absorbent member of the pad is indicated in the drawings in general by the numeral 1 and the same comprises a bag or sack 2 which may be of muslin, cheesecloth, netting, or any similar cloth material which is foraminous to a marked degree. This sack may be rectangular or any other desired contour and the same is provided with a filling 3 comprising one or more layers of sponge or any other highly absorbent and yieldable material. This member of the pad is generally of a flat form and by reason of the nature of the materials of which it is composed, it will prove soft and comfortable to the person using the

article. The absorbent member is completed by a covering 4 which may be of muslin or any other soft cloth material which is preferably less foraminous than the sack 2 so as not to prove irritating to a person resting upon the pad. It will be understood that both the sack 2 and covering 4 may be made up in any desired manner each either from one piece or several pieces the edges of which may be united by stitching or otherwise.

In order to adapt the absorbent member of the pad to be suspended as shown in Fig. 2 of the drawings and thus facilitate drying of the same, the said member is provided preferably at one end with suspension loops indicated by the numeral 5 and which loops may be formed from suitable lengths of tape in the manner clearly shown in Fig. 1 of the drawings, the ends of the lengths of tape being stitched or otherwise secured to the said end of the absorbent member. In any event, these loops are of a material which is flexible so that the loops may be folded under conditions to be presently explained.

In order to prevent bunching of the sponge or other absorbent filling 3 and to maintain the flat contour of the absorbent member as a whole, it is preferable that the member be tufted, as for example by stitches 6 run through the opposite sides of the sack 2 and through the filling 3 at suitably spaced intervals. In this manner the filling will be prevented from bunching while the pad is in use, and likewise this result will be obtained while the absorbent member is being washed or otherwise cleansed.

In order to prevent any fluids absorbed by the member heretofore described, coming in contact with the bed clothing and soiling the same, a backing sheet is provided for the absorbent member and this sheet is indicated in general by the numeral 7 and is preferably of rubberized cloth or any other flexible sheet material which is non-absorbent. This backing sheet is of the same general marginal contour as the absorbent member but of slightly greater dimensions so that at least two marginal portions thereof, for example the two end marginal portions, indicated by the numeral 8, may be folded over the corresponding ends of the absorbent member when the absorbent member is laid flat upon the spread out backing sheet 7. In order to provide for holding

2
the backing sheet assembled with the absorbent member, the latter is provided at each of its four corners, on both sides or faces of the pad, with one element 9 of a snap fastening, and the backing sheet 7 is provided at each of its four corners with the other element 10 of such a fastening. For example, the absorbent member will be provided with the stud elements of snap fasteners and the backing sheet will be provided with the socket elements of such fasteners, but if desired other types of fastening devices such for example as hooks and eyes may be employed. It will be observed by reference to Fig. 1 of the drawings that when the absorbent member is laid out upon the backing sheet 7, the suspension loops 5 will project beyond the end of the absorbent member and over the face of the backing sheet at the corresponding marginal portion 8 thereof, and in folding over the said marginal portion of the backing sheet as shown in the said figure, it will be desirable to likewise fold over the said suspension loops so that the same will be covered and protected against being torn loose, and likewise prevented from coming in contact with the patient or other person using the pad and causing irritation or annoyance.

While but a single one of the elements 9 need be provided at each corner of the absorbent pad member in order to produce a complete structure, nevertheless it will no doubt be desirable to provide two of these elements at each corner, each located upon a respective side or face of the pad member and both secured in place by the same stitches, as clearly shown in Fig. 4 of the drawings, these stitches being indicated by the numeral 11 and passing through the sack 2, the filling 3, and the covering 4. By providing these elements upon both sides or faces of the pad member, I am enabled to reverse the pad member so as to present for use a clean side thereof should the other side become soiled. It will also be evident that the stitches 11 serve as an additional means

to prevent displacement or bunching of the filling 3 in the sack.

If desired the backing sheet 7 instead of being folded over the opposite ends of the pad, may be made of such size that the ends of said backing sheet, when positioned on the pad, will terminate substantially flush 55 with the ends of said pad so that the upper face of the pad will present a smooth continuous surface.

Having thus described the invention, what is claimed as new is:—

1. A pad comprising an absorbent pad member, a backing sheet of non-absorbent material having marginal portions to be folded over upon corresponding marginal portions of the said absorbent pad member, and means for securing the said marginal portions of the sheet to the said pad member.

2. A pad comprising an absorbent pad member, a backing sheet of non-absorbent material having marginal portions to be folded over upon corresponding marginal portions of the said absorbent pad member, means for securing the said marginal portions of the sheet to the said pad member, and a flexible suspension loop carried by one of the said marginal portions of the absorbent pad member and adapted to be folded over and housed by the corresponding marginal portion of the said backing sheet.

3. In a pad of the class described, an absorbent member comprising a sack of relatively highly foraminous material, a filling of absorbent material within the sack, and a covering of less foraminous material inclosing the said sack.

4. In an article of the class described, an absorbent pad member provided upon each face with the element of a fastening device, and a non-absorbent backing sheet disposable to cover either face of the absorbent pad member and provided with the other elements of the said fastening devices.

In testimony whereof I affix my signature: 95
MARTHA V. BAUER. [L. S.]
